UNITED STATES PATENT OFFICE.

WILLIAM WURDACK, OF ST. LOUIS, MISSOURI, ASSIGNOR TO WM. WURDACK ELECTRIC MFG. CO., OF ST. LOUIS, MISSOURI, A CORPORATION OF MISSOURI.

ELECTRIC PANEL BOARD.

Application filed November 23, 1925. Serial No. 70,875.

This invention relates generally to electric wiring apparatus and devices and, more particularly, to a certain new and useful improvement in electric panel-boards.

5 My invention has for its chief objects the provision of an electric panel-board of sectional structure which may be installed with convenience and facility and which affords adjustability and flexibility in circuit arrangements and connections, and the improvement and simplification generally of electrical apparatus of the type stated.

And with the above and other objects in view, my invention resides in the novel features of form, construction, arrangement, and combination of parts hereinafter described and pointed out in the claims.

Figure 1 is a top plan view, with parts broken away and removed, illustrating a 20 two-unit sectional panel-board embodying my invention;

Figure 2 is a sectional view of the panel-board, taken approximately on the line 2—2, Figure 1;

25 Figure 3 is a sectional view taken approximately on the line 3—3, Figure 2;

Figure 4 is a top plan view of the base-member of one of the panel-board units or sections with the cover-member and all electrical elements removed;

30 Figure 5 is a diagrammatic view illustrating the wiring of a two section panel-board of my invention in connection with a three-wire main circuit and two-wire distribution for eight separate lighting circuits, there being one fuse in each circuit;

Figure 6 is a diagrammatic view illustrating the wiring of the same in connection with a three-wire main circuit and two-wire distribution for four separate lighting circuits, there being two fuses in each circuit;

35 Figure 7 is a diagrammatic view illustrating the wiring of the same in connection with a two-wire main circuit and two-wire distribution for four separate lighting circuits, there being two fuses in each circuit;

Figure 8 shows a two-unit panel of my invention enclosed within a cabinet, the latter being shown in perspective with its door 40 removed or omitted; and

Figure 9 is a section through the panel and cabinet, taken approximately on the line 9—9, Figure 8.

Referring now more in detail and by reference characters to the drawings, each of

the panel-board sections includes a base 1 constructed of suitable insulation material and molded or otherwise produced according to any desirable or customary practice. At its opposite side margins and preferably 60 near diagonally opposite corners, base 1 is recessed, as at 2, and apertured, as at 3, for accommodating bolts, screws, or the like for rigidly securing the sections in panel-board arrangement upon the usual slab or other 65 support. Base 1, which is of suitable thickness, is preferably formed upon its underside with two longitudinally elongated recesses 4, 4, communicating, respectively, at their outer ends, through openings 5, 5, with 70 recesses 6, 6, formed upon the upper face, and at the opposite ends, of base 1. Extending transversely across base 1 preferably 75 midway its ends is a channel 7, and disposed longitudinally of the base and co-inciding 80 with the recesses 6, is a channel having communication with the recesses 4 through base-openings 9, 9. Disposed lengthwise of the base or section 1 through the several aligning openings 5 and 9, with its ends fitting in 85 the recesses 6, is a cross-conducting bus-bar 10 equipped at its exposed ends with binding posts 11 loosely and removably projecting into seats or pockets 12 provided for the purpose in the base 1, the posts 11 thus functioning also, in their engagement with the base 1 at said seats 12, to detachably hold the cross-bar 10 in place.

Upon its upper face and on opposite sides of said central channel 7, base 1 is formed 90 with transverse recesses 13, 13, each including a deepened portion 14 approximately in the longitudinal middle of base 1, and also a preferably still further deepened portion 15 extending from said middle recess-portion 95 14 to one side of base 1, as best seen in Figure 4. The recesses 13 are adapted to accommodate distribution-circuit attachments or elements of the particular section or unit, as will now be described.

Seated in the transverse recesses 13 of the base, are bus-bar sections 16, attached to each of which by, and having electrical engagement with each of which only through, their center-contacts 17, is preferably a pair of fuse-plug sockets 18, the center contact 17 of one of which, as best seen in Figure 3, is of greater length than the other to project through the bar 16 to loosely seat in a pocket 19 provided for the purpose in the base 1 to 110

removably and detachably hold the bar 16 and its supported sockets 18 in place. Suitably electrically connected to and extending laterally and outwardly from the sockets 18 and suitably insulated from their respective contacts 17 are copper or other conducting strips 20 each provided at its outer free end with a binding post 21, which similarly loosely fit into respective pockets 22 provided for the purpose in the base 1 to detachably or removably retain the strips 20 in place on the upper face of the base 1 on opposite sides of the end recesses 6.

Each base-section 1 is thus loosely or detachably equipped with a longitudinally disposed conducting-bar 10 having one or more binding-posts 11 at each of its ends, two spaced and insulated transversely disposed bus-bar sections 16 extending approximately in parallel relation and each electrically supporting, as described, a pair of fuse-sockets 18 and each socket 18, in turn, having connection electrically with one of the bars 16 and with a conducting strip 20 extending outwardly upon the base and equipped with a binding-post 21, all such fixtures or attachments being preferably loosely and removably retained in position upon the base 1 merely through pocket engagement by some of the socket-contacts 17 and some of the binding posts 21.

To now operatively retain the parts in position and cover the so-called live elements of the board, I employ a cover-member 23, which is also composed of insulation material preferably similar to that of base 1, and which is adapted to fit upon and over base 1, as shown, cover member 23 being provided with counter-bored-apertures 24 for accommodating securing-screws 25 which enter tapped recesses 26 provided therefor in the base 1, whereby the cover 23 is conveniently detachably secured to the base 1 and effectively retains the several electrical elements described in place upon the base. The cover-member 23 is provided within its area with circular openings 27 for the accommodation of the fuse sockets 18, which, it may be here stated, are adapted to receive the regular fuse-plugs (not shown). At its opposite ends, the cover-section or member 23 is provided with upstanding guard-flanges 28, 28, and with preferably also triangular flanges 29, which latter project endwise from the ends of the cover-section, on opposite sides of the recesses 6 of the base-member 1, all for purposes presently appearing.

It will be understood that the panel-board, as a whole, may comprise one, two, or more of the units or sections described as may be required for the particular installation, the board being built up as required and the sections being disposed in sidewise closely adjacent or contiguous relation, as illustrated in Figures 1 and 8. For the purpose

of illustration, I here show two of the units or sections in panel-board arrangement, and for such purpose a main bus-bar 30 is disposed in the aligning channels 7 and electrically engaged, as by screws 31, with the respective cross-bars 10 of the two sections. It will be further understood that this main bus-bar 30 may be of any suitable length to electrically connect with the cross bus-bars 10 of as many sections as may be comprised in the panel-board of the particular installation, the bus-bar 30 at one end section of the complete board being provided with a terminal socket 32 for connection with a line or service wire 33. It will be also understood that in a panel-board of two or more sections, the bar-members 16 of one section are disposed in alignment and may be integrally or otherwise electrically connected with the bar-members 16 of the adjacent or contiguous section or sections.

Secured to and upon the underface of the bars 16 of the one end section of the board are suitable terminal sockets 34 for the respective main or line wires 35 and 36, the sockets 34 being accommodated in the deepened recessed portions 15 of the transverse recesses 13.

To further illustrate the flexibility of the panel-board for distribution of circuits of various types, I have shown the panel-board and its sections in connection with three different wiring systems, namely, a three-wire main circuit and two-wire circuit distribution for eight separate lighting circuits, one fuse in each circuit, as in Figure 5, a three-wire main circuit and two-wire circuit distribution for four separate lighting circuits, two fuses in each circuit, as in Figure 6, and a two-wire main circuit and two-wire circuit distribution for four separate lighting circuits, two fuses in each circuit, as in Figure 7.

In Figure 5, the electrically connected feed bar-members 16 of the several units are connected through the plugs 18 and terminal strips 20 with one side of respective distribution circuits, while the main electrically connected neutral bar-members 30 are connected through the cross-strips 10 with the other side of the respective circuits, the conveniently accessible posts 11 and 21 permitting all connections to be made with ease, facility, and convenience.

In Figure 6, the binding-posts 21 of each pair of oppositely disposed strips 20 have electrically connected thereto the out and in wires of the several distribution circuits, the main bar 30 being omitted as a service or feed connector, one set of the connected bar-members 16 being utilized as the neutral connector, and the other set of the connected bars 16 being divided, with each division connected to source, as shown.

And in Figure 7, the binding posts 21 of

each pair of oppositely disposed strips 20 have suitably electrically connected thereto the out and in wires of the several respective distribution circuits, all connections to 5 or with the main bars 30 being omitted.

In each such wiring system, which are merely illustrative of the flexibility of my new panel-board sections in wiring arrangements and connections, the conveniently accessible binding posts 11 and 21 permit all connections to be made with ease, facility, and convenience without disturbing the other elements or fixtures of the board.

It will thus be seen that a simple and practical structure is produced which conforms to the prescribed regulations for safety in panel-board installations, and which affords a wide and flexible range in both number and form of circuit arrangements and adjustments, the units being readily assembled and their several electrical fixtures being conveniently connected in various associated arrangements to comprise a single installation, which may be added to 25 or taken from, should occasion require.

Obviously, there may be other arrangements of wiring and circuits to which the panel-board of the present invention may be equally well applied, and the structure of 30 the panel-board itself and of its unit-sections may be modified in many particulars without departing from the spirit and scope of the invention as defined by the appended claims. And as illustrated in Figures 8 and 35 9, which show a two-section panel-board of my invention installed within a cabinet or box, of which box 37 designates the rear or back wall, 38, 38, the opposite side-walls, 39, 39 the opposite end-walls, and 40 an 40 apertured top-wall or trim, as it is commonly termed, the several sections co-operate with the side and end walls of the box in the formation of wiring compartments or alleys, to which alleys or compartments, when the 45 trim 40 is in cabinet completing position, the upstanding flanges 28 co-operate with the trim 40 in the formation of a so-called barrier to such compartments, the flanges 29 and the oblique inclination of their end-faces 50 protecting and guarding the posts 11 and 21 from electrical connection with an unauthorized inserted wire.

Having thus described my invention, what I claim and desire to secure by Letters Patent is:

1. A unit panel-board section including a base formed intermediate its ends and upon its under face with a pair of spaced aligning recesses and upon its upper face with spaced end recesses and an intermediate recess, there 60 being openings through the base providing communication between the under and upper recesses, said recesses providing a channel for accommodating and seating a conducting-bar.

2. In a sectional panel-board, a base having a plurality of surface-channels, and electrical elements loosely disposed upon the base and comprising bars seated in said channels, plug-sockets seated on said bars, and terminal-strips for the sockets extending outwardly of the base, in combination with means comprising a cover-section fitting upon the base and over said bars and strips for retaining the same in operative position 75 on the base, said section being apertured for accommodating said sockets, and fastening-members engaging said section and the base for detachably securing the same together.

3. In a sectional panel-board, a base, fuse-plug sockets disposed upon the base intermediate its opposite ends, a cover-member fitting over and upon the intermediate portion of the base and apertured for accommodating the sockets, the opposite end portions 85 of the base being exposed, and conducting-strips for the sockets extending outwardly of and over the exposed end-portions of the base.

4. In a sectional panel-board, a base, fuse-plug sockets disposed upon the base intermediate its opposite ends, a cover-member fitting over and upon the intermediate portion of the base and apertured for accommodating the sockets, the opposite end-portions 95 of the base being exposed, conducting-strips for the sockets projecting outwardly of and over the exposed end-portions of the base, binding-posts supported by and at the outer ends of the strips, and guard-flanges upon 100 the cover-member for the strips and posts.

In testimony whereof, I have signed my name to this specification.

WILLIAM WURDACK.
